ABSTRACT: A tool having a central mandrel movable axially within an outer body for expanding metal friction locks and an elastomeric packer to anchor the tool and form a pressure seal within a surrounding well conduit. Anchoring and release is assisted by a fluid bypass formed across the packer which is gradually closed or opened by the moving mandrel as the tool is set or released. A slack joint in the outer body accommodates small movements of the mandrel when the tool is anchored to prevent inadvertent release and an insulated electrical conductor extends axially through the bar to energize and monitor a transducer secured below the seal.

BOTTOM-HOLE SHUT-IN TOOL

BACKGROUND OF THE INVENTION

1. Field of the Invention

The present invention relates generally to the field of well drilling, completion and production. More specifically, the present invention relates to a new and improved bottom-hole shut-in tool for sealing a well conduit at a subsurface location and for maintaining electrical contact with instruments secured to the tool.

2. Description of the Prior Art

The evaluation of petroleum wells often requires information regarding the pressure of the oil or gas in the formation being produced or drilled. Such information is normally obtained by sealing the well at the well head and recording the changes in well pressure, or, by sealing the well at the desired subsurface location with a shut-in tool and recording pressure changes with a self-contained transducer-recorder carried below the tool.

For meaningful results, the data obtained by the first method must be corrected for the effects of after flow which are particularly significant in long tubing strings or low permeability wells. This is normally done by recording pressure changes over a relatively long period of time and applying correction factors dependent upon the length of the tubing string, the weight and viscosity of the fluid in the string, the porosity of the formation and other factors.

The second method also involves a significant time loss since the information gathered during the test cannot be evaluated until the recorder has been brought back to the surface. Moreover, since this method provides no means for surface monitoring of the testing instrument, a malfunction of the instrument is not discovered until it is recovered from its subsurface location. In such instances, the entire testing procedure must be repeated with a corresponding loss in time.

The shut-in tools required in the second method may also give rise to problems when a high pressure differential exists across the tool. If the packer customarily employed in such tools is released too quickly, a high pressure acting below the tool may blow the tool up-hole causing damage to the equipment or the well. On the other hand, during the setting procedure, the tool may also be displaced if it is not securely anchored against the well conduit before the elastomeric packer begins to seal off the down-hole pressure. In certain shut-in tools, a high pressure differential may also cause partial release of the tool's setting mechanism with a resultant decrease in the anchoring and sealing forces exerted against the well conduit.

SUMMARY OF THE INVENTION

The shut-in tool of the present invention includes a segmented central mandrel carried within an outer body which includes metal anchoring means or slips and an expandable packer of resilient material. The tool is suspended on electrical wire line and the slips and packer are expanded by a subsurface setting tool to securely anchor the tool in position and form a pressure barrier in the conduit.

The effects of a pressure differential across the packer which normally tend to displace the tool, are controlled by a fluid bypass which provides gradual pressure changes across the packer as the tool is being set or released. Once set in the well conduit, the slips are prevented from being inadvertently released under the influence of down-hole pressures by means of a slack joint provided in the outer tool body which permits upward movement of the central mandrel to wedge the slips more securely against the conduit wall.

The central mandrel carries an insulated electrical conductor which may be electrically connected between the conductor in the wire line and a transducing instrument secured to the lower end of the tool to permit constant monitoring of the output of the transducer at the well surface. When the shut-in tool is employed with a motor-driven setting tool, it may be repeatedly set and released for measuring static characteristics

of the well at different subsurface locations without having to retrieve the tool after each test. Since the well conduit is sealed at the desired test depth, the effects of after flow are eliminated from the test results, thereby eliminating much of the delay associated with other methods and devices. When flowing well characteristics are desired, they may be obtained by simply monitoring the transducer with the shut-in tool unset.

From the foregoing description, it may be seen that the bottom-hole shut-in tool of the present invention lends itself to rapid wire line usage and permits constant, surface monitoring of a down-hole transducer to provide immediate and positive data on well and formation quality under both static and flowing conditions. Moreover, with the tool of the present invention, a series of tests may be conducted at different subsurface locations without having to remove the tool from the well between each test. These and other features and advantages of the present invention will be more apparent from the following specification and related drawings.

BRIEF DESCRIPTION OF THE DRAWINGS

FIG. 1 is a vertical cross section of a cased well illustrating the bottom-hole shut-in tool of the present invention set in the well conduit;

FIGS. 2A and 2B constitute a partial elevation, partially broken away, illustrating the bottom-hole shut-in tool of the present invention in its unset condition; FIG. 2B is a lower continuation of FIG. 2A;

FIG. 3 is an enlarged cross section taken along the line 3-3 of FIG. 2A;

FIG. 4 is an enlarged cross section taken along the line 4-4 of FIG. 2B;

FIG. 5 is an enlarged partial elevation, partially in section, illustrating details in the slack joint of the shut-in tool in its open position;

FIG. 6 is a partial elevation, partially in section, illustrating the shut-in tool in set position; and

FIG. 7 is a partial elevation, partially in section, illustrating a modified form of the shut-in tool.

DESCRIPTION OF THE PREFERRED EMBODIMENTS

With reference to FIG. 1 of the drawings, the shut-in tool 10 of the present invention is illustrated in set position against the interior walls of a well conduit C with a motor-driven setting tool S secured to the top of the tool 10 and a transducing instrument T secured to its lower end. The entire tool string is suspended in the conduit C by means of an electrical wire line L which provides electrical power and an electrical pathway for the equipment attached to the line. The line L is lowered into and withdrawn from the conduit C by conventional wire line apparatus (not illustrated) located at the well surface.

The setting mechanisms may be any suitable device which is capable of setting and releasing the shut-in tool 10 while also providing the required electrical linkage between the wire line L and the tool. One such setting mechanism invented by the present applicant is described in U.S. Pat. application Ser. No. 764,763 filed Oct. 3, 1968, entitled "Electric Setting Mechanism for Subsurface Well Tools." As more fully described in said application, the setting tool S includes means for holding the outer body of the tool 10 stationary while axially moving a central mandrel extending through the tool 10, and further means for providing an insulated electrical conducting path between the wire line L and the tool 10.

The instrument T may be any transducer which converts well conditions such as pressure and temperature into an electrical signal. If desired, a conventional, self-contained transducer-recorder may also be secured to the tool string as a backup for the transducer T. It should also be noted that additional equipment not illustrated such as a collar locator, weight bars, jars or other tools may be connected into the tool string if required.

The shut-in tool 10 includes metal slips 11 which are expanded radially when the tool is set to grip the interior wall of the conduit C and anchor the tool in place. As will hereinafter be described in greater detail, the setting procedure also foreshortens an elastomeric packer 12 causing it to expand radially and bear against the conduit C to create a pressure seal.

The tool 10 is initially lowered into the conduit C with the slips 11 and packer 12 retracted. When a desired testing depth is reached, as for example above perforations C' which open into the formation, the setting tool S is energized to expand the slips and packer. The transducer T is then switched into the wire line circuit to transmit its output to a surface monitoring station. Setting of the tool 10, as illustrated in FIG. 1, seals the area A below the packer 12 from the area B above the packer, and the condition of the formation may be tested without regard to the effects of after flow.

The structure of the tool 10 is best illustrated in FIGS. 2A and 2B, where it is seen to include an adapter fitting 16 secured to the slips 11, and a tapered, cylindrical cone member 14 secured to a cylindrical body member 13 which extends from the slips 11 to the packer 12. A segmented center mandrel 15 extends coaxially through the members 16, 11, 14, 13, and 12, and is employed to set and release the tool as well as to provide an insulated electrical pathway between the wire line L and the transducer T. The tool 10 is secured to the setting tool S by means of the adapter fitting 16 with the mandrel 15 extending upwardly through the fitting 16 and connecting to the movable portion of the setting tool S.

With reference jointly to FIGS. 2A and 5, the fitting 16 includes a partially threaded upper portion 16' which is slidably received in the lower socket S' of the setting tool and a lower member 16'' which is threadedly engaged with the slips 11. In attaching the tool 10 to the setting tool S, the threads on the portion 16' are advanced past the threads in the socket S' to form a slack-joint indicated generally at 17 which permits limited axial movement of the fitting 16 within the socket S'. As will hereinafter be more fully explained, the slack-joint 17 prevents inadvertent release of the tool 10 when a high pressure differential exists across the packer 12.

Referring to FIGS. 2A, 2B, 3 and 4, the central mandrel 15 is composed of a series of threadedly engaged segments 15a, 15b, and 15c. Each segment includes an electrical conductor 18a, 18b, and 18c respectively disposed within a protective insulating covering 19a, 19b and 19c respectively. The conductors 18b and 18c have a solid cross section while the conductor 18a has a tubular form which is adapted to receive a stationary solid conductor S'' extending from the setting tool S. As more fully described in said application Ser. No. 764,763, the conductors 18a and S'' cooperate to maintain continuous, sliding electrical contact between the conductors in the tool 10 and the conducting path in the setting tool as the mandrel 15 is moved axially during the setting and release motions. For the purposes of the present invention, however, any suitable means for maintaining electrical contact between the movable mandrel 15 and the setting tool S may be employed.

As illustrated in FIGS. 2A and 2B, the mandrel sections 15a and 15b are threadedly engaged with an O-ring 20a of resilient material such as rubber or other suitable material disposed between the two sections to provide a leakproof seal. Electrical contact between the conductors 18a and 18b carried in the two adjoining mandrel sections is made by means of a separable connector 21a. Similarly, the sections 15b and 15c are threadedly engaged with two O-rings 20b and 20c disposed between the two sections with a second separable connector 21b providing electrical contact between the conductors 18b and 18c.

The lower end of the mandrel section 15c threadedly engages a backup connector fitting 22 with a single O-ring 20d disposed between the two members. The electrical circuit between the conductor 18c and the circuitry of the transducer T is completed by means of a third separable connector 21c provided at the lower end of the mandrel section 15c. The

connector 21c includes an outer insulating body 21c' which is disposed in a central bore formed in the fitting 22. A counter sunk set screw 21c'' extends through the body 21c' to retain the metal receptacle portion of the connector in place.

5 The transducing instrument T is mechanically secured to the tool 10 by means of threads 22a formed at the lower end of the fitting 22. An O-ring (not illustrated) similar to those employed at the joints of the mandrel sections is also employed to provide a leakproof joint between the transducer T and the fitting 22. Electrical connection is completed by inserting a suitable male connector element from the transducer T into the lower metal receptacle provided in the connector 21c.

As illustrated in FIG. 2B, the packer 12 is disposed between an upper bearing member 23 and a lower bearing member 24. The bearing member 23 is threadedly engaged at one of its ends to the body member 13 and its lower end is provided with a concave surface 23a which is adapted to bear against a convex end surface 12a on the packer 12. The upper end of the bearing member 24 is also provided with a concave surface 24a which is adapted to bear against a lower convex end surface 12b on the packer 12. The lower end of the member 24 is provided with a convex surface which is seated in a concave surface formed at the upper end of the fitting 22. The packer 12 is disposed over a sleeve 25 which extends from the internal bore of the cone member 14 to a socket formed in the member 24. The sleeve 25 is free to move axially with respect to the member 24 with the lower end surface of the sleeve being adapted to bear against an internal shoulder 24b formed 10 in the socket of the bearing member 24.

In setting the shut-in tool 10, the setting tool S holds the slip member 11 stationary while pulling the mandrel 15 upwardly. This upward movement is transmitted through the backup fitting 22 which in turn forces the bearing member 24 upwardly to compress the packer 12. During the initial compression of the packer 12, the bearing member 23 is also forced upwardly causing an upward movement of the cone member 14. Referring specifically to FIGS. 2A, 3 and 6, the cone member 14 is provided with a tapered, convex surface 14a which is adapted to slide under resilient metal fingers 11a formed on the slips 11. During the setting of the tool 10, the member 14 moves upwardly with respect to the slips 11 causing the surface 14a to bear against tapered internal surfaces 11b formed on each of the slip fingers 11a which in turn expands the fingers radially outwardly. When sufficient radial expansion has occurred, teeth 11c formed on the outer surface of the fingers 11a bear against the internal wall of the well conduit C to frictionally lock the tool 10 in position.

50 When the surface 14a is tightly wedged under the slip fingers 11a, further upward movement of the cone member 14 is prevented and, thereafter, as illustrated in FIG. 6, continued upward movement of the mandrel 15 acts to further compress the packer 12 causing it to seal tightly against the internal wall 55 of the conduit C.

As previously stated, the effects of differential pressure across the packer 12 which would normally tend to dislodge the tool from its set position are compensated for by the slack joint 17. This feature of the shut-in tool 10 may best be described by referring to FIGS. 2A, 5 and 6. When the tool 10 is being set, the upward motion of the mandrel 15 draws the slack joint into the closed position illustrated in FIG. 2A. Once the tool 10 is in the set position illustrated in FIG. 6, a sufficiently high pressure below the packer 12 will drive the center mandrel 15 upwardly by further compressing the packer 12. The mandrel will in turn exert a lifting force on the set tool S causing the slack joint 17 to open as illustrated in FIG. 5. The lost motion provided by the slack joint 17 thereby prevents the 60 upward movement of the mandrel 15 from exerting a lifting force on the slip member 11. The operation of the slack joint 17 also acts to more securely anchor the tool 10 since the upward mandrel movement is also conveyed through the packer 12 to increase the force exerted by the tapered surface 14a against the slip fingers 11.

The effects of a pressure differential across the tool are also compensated for by means of a closeable fluid bypass which is provided across the packer 12 to permit gradual pressure changes across the packer as it is set or released. As illustrated in FIGS. 2A and 6, the closeable fluid bypass includes radial bores 24c and 25a which extend through the bearing member 24 and sleeve 25 respectively. An annular space 26, formed between the sleeve 25 and the mandrel section 15, extends to a second set of radial bores 25b which are formed in the sleeve 25. The bypass continues through the space formed between the outer surface of the sleeve 25 and the inner surfaces of the body member 13 and bearing member 23 and is completed through radial bores 23b formed in the member 23.

Complete closure of the bypass is effected when the mandrel section 15c and sleeve 25 are drawn into the body member 13 as the tool 10 is set. Thus, with reference to FIG. 6, it is seen that when the tool 10 is set, the bypass around the packer 12 is closed by O-rings 27, 28 and 29. In both the set and unset positions of the tool 10, the O-ring 27 forms a continuous seal between the mandrel section 15c and the sleeve 25 while the O-ring 28 forms a continuous seal between the sleeve 25 and the body member 13. When the mandrel section 15c is pulled upwardly, the O-ring 29 is drawn into engagement with the reduced internal bore in the body member 13 to close the bypass and shut-in the well below the packer 12.

When retrieving the tool 10, the initial downward movement of the mandrel 15 opens the bypass without releasing the slips 11 and packer 12 which remain firmly secured against the conduit C. With the bypass open and the tool 10 set, gradual reduction of the pressure differential across the packer 12 is permitted to prevent the tool 10 from being blown up-hole. When the pressure differential has been sufficiently reduced, the tool 10 is disengaged from the conduit C by moving the mandrel 15 downwardly permitting the packer 12 and slips 11 to return to their retracted positions.

It should be noted that the form of the invention illustrated in FIGS. 1-6 is intended primarily for use in those applications where the pressure below is greater than that above the packer 12. When the pressure above the packer 12 is greatest, the relative positions of the cone member 14 and slips 11 are reversed with the cone member 14 being disposed above the slips 11 to ensure firm anchoring against the well conduit.

While the invention has been thus far described with only a single packer 12, any number of packers may be employed. Thus, as illustrated in FIG. 7, a plurality of packers 112 may be spaced below the body member 113 along the body of the tool with each packer being disposed directly over the central mandrel 115 between bearing members 123 similar to the members 23. The members 123 are, in turn, engaged with external threads formed at each end of suitable tubular spacing members 113 similar to the body member 13. If a bypass is desired, the bottom packer 112 may be mounted over a sleeve 125 in a manner similar to that illustrated in FIGS. 2B and 6. It will be understood that the upper portion of the tool is similar to the first form of the invention illustrated in FIGS. 1-6.

The second form of the invention illustrated in FIG. 7 provides greater contact between the tool and the well conduit and thus effects a stronger seal. If the formation to be evaluated is one of several producing zones in the same well conduit, the shut-in tool illustrated in FIG. 7 may be employed as a straddle pack-off to seal in the zone above and below the perforations opening into the zone to be evaluated. In such an application, the transducing instrument is positioned in the body of the tool between the packers to permit testing of the sealed in zone.

The foregoing disclosure and description of the invention is illustrative and explanatory thereof, and various changes in the size, shape and materials as well as in the details of the illustrated construction may be made within the scope of the appended claims without departing from the spirit of the invention.

I claim:

5. 1. A bottom-hole shut-in tool assembly operable by a setting mechanism for sealing a well conduit at a subsurface location and monitoring well conditions within a sealed portion of the well comprising:

- a. a tool body having first and second axially spaced ends;
- b. anchoring means included between said first and second ends of said body for mechanically anchoring said body to the surrounding walls of the conduit;
- c. sealing means included between said first and second ends of said body for forming a seal between said body and the well conduit;
- d. setting means included in said body and movable by the setting mechanism for moving said anchoring means and said sealing means into and out of engagement with the well conduit;
- e. circuit means carried in said body for conveying electrical energy between said first and second ends of said body; and
- f. transducing means connected with said circuit means for generating electrical signals representative of well conditions.

2. The shut-in tool as defined in claim 1 further including:

- a. bypass means extending across said sealing means for permitting pressure equalization across said sealing means while said sealing means is sealed against the well conduit; and
- b. control means for opening and closing said bypass means while said sealing means is sealed against the well conduit.

30 3. The shut-in tool as defined in claim 1 above further including lost motion means for permitting said setting means to be moved by differential well pressure across said packer without moving said anchoring means out of engagement with the well conduit.

35 4. The shut-in tool as defined in claim 2 further including lost motion means for permitting said setting means to be moved by differential well pressure across said packer without moving said anchoring means out of engagement with the well conduit.

5. The shut-in tool as recited in claim 1 wherein:

- a. said setting means includes a mandrel having first and second ends extending internally between said first and second ends of said body; and
- b. said circuit means includes one or more electrical conductors carried within and electrically insulated from said mandrel.

6. The shut-in tool as defined in claim 5 wherein:

- a. said mandrel includes a plurality of adjoining mandrel sections;
- b. each of said mandrel sections includes connecting means for mechanically securing said adjoining mandrel sections to each other; and
- c. each of said mandrel sections further includes a section of electrical conductor and a separable electrical connector means at each end of adjoining ends of said mandrel sections for making electrical contact between said conductor sections in adjoining mandrel sections.

55 7. The tool as defined in claim 5 wherein:

- a. said anchoring means includes a plurality of movable locking members having friction producing means on their external surfaces;
- b. said anchoring means further includes axially movable spreader means for radially moving said locking members into engagement with the internal surface of the well conduit;
- c. said sealing means includes at least one radially expandable elastomeric packer member for engaging the internal surface of the well conduit; and
- d. said setting means including means for axially moving said mandrel relative to said anchoring means, spreader means and elastomeric packer member.

8. The tool as defined in claim 7 further including:

a. a bearing member secured to one end of said mandrel for axially moving said elastomeric member and spreader means when said mandrel is moved from said second toward said first end of said body; and

b. attachment means on a said bearing member for mechanically and electrically securing electrical equipment to said tool.

9. The tool as defined in claim 5 wherein:

a. said first end of said body includes lost motion means for mechanically connecting said body to the setting mechanism and providing limited axial movement of said body relative to the stationary portion of the setting mechanism;

b. said anchoring means includes slips having a plurality of slip fingers extending axially from a tubular base;

c. said anchoring means further includes an axially movable spreader means having a convex external surface for expanding said slip fingers radially;

d. said sealing means includes a tubular elastomeric packer;

e. said first end of said mandrel includes means for mechanically and electrically securing said mandrel to the movable portion of the setting mechanism;

f. said second end of said mandrel includes a bearing member for limiting the axial movement of said packer and spreader in a direction from said first to said second end of said body;

g. said bearing member includes attachment means for mechanically and electrically securing electrical equipment to said tool; and

h. said mandrel is movable relative to said body whereby motion of said mandrel in a direction from said second to said first end of said body moves said bearing member toward said first end of said body and compresses and radially expands said packer and moves said spreader axially to expand said slip fingers radially.

10. The tool as defined in claim 9 further including:

a. bypass means extending across said sealing means for permitting pressure equalization across said sealing means while said sealing means is sealed against the well conduit; and

b. control means for opening and closing said bypass means while said sealing means is sealed against the well conduit.

11. The tool as defined in claim 10 wherein said bypass means includes:

a. a tubular sleeve having first and second axially spaced ends disposed between said packer and said mandrel;

b. an annular passage between said sleeve and said mandrel extending axially between said first and second sleeve ends;

c. inlet means adjacent said second sleeve end extending through said body and sleeve and into said annular passage; and

d. outlet means adjacent said first sleeve end extending through said body and sleeve and into said annular passage.

12. The tool as defined in claim 11 above wherein said control means includes;

a. first sealing means adjacent said first sleeve end for forming a continuous seal between said mandrel and said first end of said sleeve;

b. second sealing means adjacent said first sleeve end for forming a continuous seal between said sleeve and said body; and

c. third sealing means axially disposed between said first and second sealing means for forming a seal between said sleeve and said body to close said outlet means when said mandrel is moved in a direction from said second toward said first body end.

13. The tool as defined in claim 5 further including:

a. bypass means extending across said sealing means for permitting pressure equalization across said sealing means while said sealing means is sealed against the well conduit; and

b. control means for opening and closing said bypass means while said sealing means is sealed against the well conduit.

14. The tool as defined in claim 5 further including lost motion means for permitting said setting means to be moved by differential well pressure across said packer without moving said anchoring means out of engagement with the well conduit.

15. The tool as defined in claim 13 wherein:

a. said mandrel includes a plurality of adjoining mandrel sections;

b. each of said mandrel sections includes connecting means for mechanically securing said adjoining mandrel sections to each other; and

c. each of said mandrel sections further includes a section of electrical conductor and a separable electrical connector means at each end of adjoining ends of said mandrel sections for making electrical contact between said conductor sections in adjoining mandrel sections.

16. The tool as defined in claim 14 wherein:

a. said mandrel includes a plurality of adjoining mandrel sections;

b. each of said mandrel sections includes connecting means for mechanically securing said adjoining mandrel sections to each other; and

c. each of said mandrel sections further includes a section of electrical conductor and a separable electrical connector means at each end of adjoining ends of said mandrel sections for making electrical contact between said conductor sections in adjoining mandrel sections.

17. The tool as defined in claim 6 further including:

a. bypass means extending across said sealing means for permitting pressure equalization across said sealing means while said sealing means is sealed against the well conduit;

b. control means for opening and closing said bypass means while said sealing means is sealed against the well conduit; and

c. lost motion means for permitting said setting means to be moved by differential well pressure across said packer without moving said anchoring means out of engagement with the well conduit.

18. The tool as defined in claim 17 wherein:

a. said lost motion means includes means for mechanically connecting said first end of said body to the setting mechanism and providing limited axial movement of said body relative to the stationary portion of the setting mechanism;

b. said anchoring means includes slips having a plurality of slip fingers extending axially from a tubular base;

c. said anchoring means further includes an axially movable spreader means having a convex external surface for expanding said slip fingers radially;

d. said sealing means includes a tubular elastomeric packer;

e. said first end of said mandrel includes means for mechanically and electrically securing said mandrel to the movable portion of the setting mechanism;

f. said second end of said mandrel includes a bearing member for limiting the axial movement of said packer and spreader in a direction from said first to said second end of said body;

g. said bearing member includes attachment means for mechanically and electrically securing electrical equipment to said tool; and

h. said mandrel is movable relative to said body whereby motion of said mandrel in a direction from said second to said first end of said body moves said bearing member toward said first end of said body and compresses and radially expands said packer and moves said spreader axially to expand said slip fingers radially.

19. The tool as defined in claim 17 wherein said bypass means includes:

a. a tubular sleeve having first and second axially spaced ends disposed between said packer and said mandrel;

9

- b. an annular passage between said sleeve and said mandrel extending axially between said first and second sleeve ends;
  - c. inlet means adjacent said second sleeve end extending through said body and sleeve and into said annular passage; and
  - d. outlet means adjacent said first sleeve end extending through said body and sleeve and into said annular passage.
20. The tool as defined in claim 19 wherein said control means includes:
- a. first sealing means adjacent said first sleeve end for forming a continuous seal between said mandrel and said first end of said sleeve;
  - b. second sealing means adjacent said first sleeve end for forming a continuous seal between said sleeve and said body; and
  - c. third sealing means axially disposed between said first and

10

second sealing means for forming a seal between said sleeve and said body to close said outlet means when said mandrel is moved in a direction from said second toward said first body end.

5 21. The tool as defined in claim 17 further including a plurality of axially spaced elastomeric packers carried between said first and second ends of said body.

22. The tool as defined in claim 18 further including a plurality of axially spaced elastomeric packers carried between said first and second ends of said body.

15 23. The well tool assembly as defined in claim 1 further including monitoring means disposed above said sealing means and connected with said circuit means for providing an output signal representative of said well conditions contemporaneously with the generation of said electrical signals by said transducing means.
